Primary Examiner — Rosemary K Tarcza
Assistant Examiner — Lacey Chey Bowman(57) **CLAIM**

The ornamental design for a camera, as shown and described.

DESCRIPTION

FIG. 1 is a top, front and right side perspective view of a camera showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate portions of the camera which form no part of the claimed design.

The oblique shade lines in the drawings represent reflective surfaces.

1 Claim, 8 Drawing Sheets(56)
